DESIGN FOR AN AIR COMPRESSING UNIT

Ivan L. Eastman, Toledo, Ohio, assignor to The
De Vilbiss Company, Toledo, Ohio, a corpora-
tion of Ohio

Application July 13, 1940, Serial No. 93,601

Term of patent 14 years

To all whom it may concern:

Be it known that I, Ivan L. Eastman, a citizen of the United States and resident of Toledo, in the county of Lucas and State of Ohio, have invented a new, original, and ornamental Design for an Air Compressing Unit, of which the following is a specification, reference being had to the accompanying drawing, forming a part thereof.

In the drawing, Figure 1 is a side elevational view of an air compressing unit showing my new design; and Figure 2 is a view of the right

hand end of the air compressing unit shown in Figure 1.

The side of the compressing unit opposite to that shown in Figure 1 is identical thereto in appearance except that the opposite side does not have the electric toggle switch shown at the extreme left in Figure 1.

I claim:

The ornamental design for an air compressing unit, substantially as shown and described.

IVAN L. EASTMAN.
